JOSEF OLINGER, OF FRAULAUTERN/SAARGEBIET, GERMANY.

LOCK.

Application filed May 1, 1926, Serial No. 106,116, and in Germany August 20, 1925.

The invention relates to an improved lock for use on doors of railway goods trucks, motor cars, motor cycles, cycles, window fastenings and the like.

5 The locking device of the lock takes the form of a bolt which passes right through the whole of the lock casing and projects at both ends. Inside the lock casing the bolt has mounted upon it a cylindrical sheath 10 upon which rotatable locking discs are arranged, which are provided with spring controlled peg members projecting through a recess on the exterior of the casing. On the exterior of the case an indication slot is provided for the setting of the controlling number for which the lock is intended, the setting being effected by turning the peg members within slots provided for the purpose. The numbers associated with the discs thus 20 become visible in succession and each peg member is moved until its corresponding number appears. The peg members themselves are meanwhile kept under tension whereby the discs are held firmly in their set 25 position. After this setting has been effected a double lever controlled by a spring comes automatically into operation and engages through the medium of pins arranged on it in setting holes in the rotatable locking discs, 30 the peg members of which are then returned to their positions of rest. The actuation of the double lever however also causes the withdrawal of a locking cam which engages in the locking bolt, so that both the bolt and the lock 35 can be moved relatively to one another. This opening of the lock simultaneously causes a slide to move forward under the indication slot whilst, besides this the locking discs are engaged in an axial direction by a fork 40 member rigidly connected to the locking bolt and are thus prevented from rotating. The bolt, which is controlled by a spring, is then fixed by means of a locking device.

In order to put the lock into use the locking device is released again, whereupon the locking bolt or the lock respectively flies back into the locked position under the influence of a spring. During this operation a projecting arm carried by the locking bolt 45 acts in such a manner on the double lever that the locking cam again engages the locking bolt whilst the pins of the double lever simultaneously emerge again from the locking discs, which latter are also now disengaged from the fork.

The rotatable locking discs now fly back

under the influence of the helical tension springs into their original position, in which the peg members once again project. The return movement of the slide member which 60 covers the set lock number is retarded.

Constructional forms of the invention are illustrated by way of example in the accompanying drawings, Figs. 1 to 5, in which:

Fig. 1 is an elevation of the lock as applied to a padlock, 65

Fig. 2 is a medial vertical section, with a part in elevation.

Fig. 3 is a section through a rotatable locking disc on the line A—B of Fig. 2, 70

Fig. 4 is a detail showing the parts operating the locking cam and

Fig. 5 is a plan of the slide for the indication slot.

The casing 1, which is preferably cylindrical, is closed on the right and left hand sides by means of screw nuts which are soldered, brazed or welded on. The locking bolt 4 passes through the middle of the lock and has mounted upon it the partly open cylinder 5, which passes into the broader cylindrical part 6. On the cylinder 5 several rotatable locking discs 29, 30, 31 and 32 are mounted in grooves or the like, these discs being provided with projecting rotatable adjusting peg members 39, which are under the influence of the helical springs 38. The peg members 39 project out in their end position through the slots 40 in a recess 12 of the casing 1 in such manner as to be operable by hand. Each of the rotatable discs 29—32 is provided at its side with a setting ring 33 marked with a scale of numbers, viz 1 to 9 and 0. 75

This ring is held frictionally on the disc 95 so as to allow of being adjusted for changing the position of the number relative to the peg members.

In order to open the lock the peg members 39 projecting in the recess 12 are pushed upwards successively going from left to right, the corresponding rotatable discs being carried with them in their motion. Since the pegs in moving upwards are subjected to increasing tension they are preferably turned round so as to lie transverse to the slots 40 and are pushed up over the exterior edges of the latter. During this operation the numbers appear below the indication slot 11 in the casing, as shown for example in Fig. 1 for the numbers 1, 2, 4, 8. 100
105
110 The setting of the rotatable locking discs

(which are held in position by the peg members) in this way to the key number of the lock, which is different for each individual lock causes the pins 34 on the arm 17 of the 5 double lever 16, 17 which is pivoted at 18, to engage in the holes 35 of the rotatable locking discs 29—32, said holes being now in position immediately beneath said pins and the arm 16 of the double lever being 10 pressed upwards by the helical spring 14 and so depressing the arm 17. Simultaneously the locking cam 15 fixed to the arm 16 emerges from the bolt notch 9 and releases the locking bolt 4.

15 In the case of a padlock as shown in Fig. 1 where the locking bolt 4 engages in the end 3 of the shackle 2, the locking bolt 4, which is under the influence of the helical spring 8 resting on the ring 7, is drawn 20 back and locked in the open position by means of the click 13 engaging in the notch 10 of the locking bolt. As the locking bolt 4 is drawn back the fork arm 22 which is attached to it also moves back together with 25 the fork pins 20 and 21 mounted on the said fork arm whereby the pins are guided into the holes 36 of the discs 29—32. The operations are similar in the case of the lock construction shown in Fig. 2, but in this 30 case, if the locking bolt 4 is immovably mounted; the lock has to be pushed over instead of the bolt being drawn back in order to effect the above mentioned operations and bring the lock into the fully 35 unlocked position in which it is held by means of the click 13. When the lock is in the fully unlocked position the fork arm 22 will also have moved the slide 26, which is rotatably pivoted at 27 and is pressed against 40 the fork arm 22 by a spring, into the position in which they key number is covered.

The projecting peg members which are still in the positions corresponding to the setting of their respective rotatable discs are 45 now turned once again into positions longitudinal to the slots 40 and are thus caused to fly back below the casing 1 under the action of the helical springs 38.

As is shown in Figs. 2 and 3, the rotatable 50 locking discs 29, 30 and 31 are not only provided with adjusting holes for the pins 34, but also with a number of irregularly arranged so-called blind holes 35 having very little depth. These blind holes serve the 55 purpose of misleading unauthorized persons in any endeavour to open the lock and to render it impossible to find the correct setting holes.

The locking disc 32, on the other hand, 60 has only one adjusting hole 35, which is preferably arranged in a somewhat recessed position, in order to render it impossible for an unauthorized person to find the setting hole on this disc by testing out by hand.

65 According to the preceding arrangement

it is essential that the owner of the lock should set the key number from left to right. In the event of the setting having been effected in the wrong order, in which case the discs are at once locked by the engagement of the pins 34, it is possible to cause the locking discs to move back into their original position under the action of the helical springs 37 by depressing the arm 16 of the double lever by means of a thin 70 object introduced through the oiling hole 41.

In order to close the lock the click 13 is released and the locking bolt 4 flies back into the locked position or if the locking bolt is immovably mounted, the lock moves into 80 the said position under the influence of the spring 8. During this operation the fork pins 20 and 21 connected with the locking bolt 4 first move back out of the openings 85 36 of the locking discs 29—32. The projecting arm 23 connected with the locking bolt 4 through the medium of the fork arm 22 simultaneously moves and causes its cam 25, which has been brought into the position of engagement from its otherwise non-engaging position by means of the spring 24, to slide over the lever arm 16 and, in passing the cam 19 of the arm 16, to press the locking cam 15 back into the notch 9 of the bolt, with the result that the lever arm 17 with its pins 90 34 comes out of engagement with the setting holes 35 of the locking discs 29—32, the latter being meanwhile moved back into their original position by the action of the helical springs 37. Besides this the slide 100 26 is again pushed back by the contact of the fork arm 22 with the projection 28 and exposes the indication slot 11 for re-setting from left to right after the key number of the lock has already become invisible. The 105 key number of the lock depends upon the adjustment of the number of rings 33 carried by the rotatable discs 29—32 which rings can, if necessary, be altered to a new 110 number.

When the shackle 2 shown on Fig. 1 is omitted the lock constructed in accordance with Fig. 2 can be employed for a large number of different purposes, as mentioned above. It is especially applicable in cases 115 where the lock itself or the locking bolt 4 is rigidly attached to the object which is to be locked.

The details of construction may be varied in numerous ways without departing from 120 the scope of the invention.

I claim:

1. In locks the combination of: a casing having a recess and slots formed in the wall of said recess, with a spring controlled locking bolt passing through said casing, a cylindrical member mounted on said locking bolt, rotatable locking discs mounted on said cylindrical member and having peripheral setting holes and so-called blind holes, helical 125 130

tension springs controlling the rotary movement of said locking discs, means for engaging said setting holes when said locking bolt is in the unlocked position and releasing said setting holes when said locking bolt is in the locked position, adjustably mounted setting rings fixed to said locking discs and peripherally marked with numbers, and rotatable spring controlled peg members fixed 5 on said discs and serving for the setting and holding in position of said discs, said peg members passing through said slots and being operable by hand from the exterior of the casing, substantially as described.

10 2. In locks, the combination of: a casing having a recess and slots formed in the wall of said recess, with a spring controlled locking bolt having a notch and passing through said casing, a cylindrical member mounted 15 on said locking bolt, rotatable locking discs mounted on said cylindrical member and having peripheral setting holes and so-called blind holes, helical tension springs controlling the rotary movement of said locking 20 discs, setting rings mounted adjustably on said locking discs and peripherally marked with numbers, rotatable spring-controlled 25 peg members fixed on said discs and serving for the setting and holding in position of said discs, said peg members passing through 30 said slots and being operable by hand from the exterior of the casing, a spring controlled double lever, locking pins on one arm of said lever adapted to engage said setting holes, a locking cam on the other arm 35 of said lever adapted to engage said notch on said locking bolt, said locking pins and locking cam serving for alternately locking and releasing said rotatable discs and said locking bolt, a fork member, pins on said 40 fork member engaging with and holding in position said locking discs when the lock is open, and a projecting arm on said fork member carrying a resiliently mounted cam, said locking bolt on the closing of the lock 45 drawing back said pins so as to release said discs and simultaneously locking itself by causing said resiliently mounted cam to depress said double lever and so bring said locking cam into engagement with said locking bolt.

In testimony whereof I have hereunto set my hand.

JOSEF OLINGER.
